UNITED STATES PATENT OFFICE.

JOHN M. PATTERSON, OF LA FAYETTE, GEORGIA.

DOOR-STOP.

No. 914,179.

Specification of Letters Patent.

Patented March 2, 1909.

Application filed May 21, 1908. Serial No. 434,204.

To all whom it may concern:

Be it known that I, JOHN M. PATTERSON, a citizen of the United States, residing at La Fayette, in the county of Walker and State of Georgia, have invented a new and useful 5 Door-Stop, of which the following is a specification.

This invention relates to door stops and has for its object to provide a comparatively 10 simple and inexpensive device of this character especially designed for attachment to a floor or other suitable support for holding the door in open or partially open position.

A further object of the invention is to provide 15 a door stop including a supporting frame having a spring catch secured thereto and arranged in the path of movement of the door for engagement with the lower edge thereof thereby to prevent accidental swinging movement of the door.

A further object is to provide means for adjusting the pivoted end of the catch vertically of the supporting frame, and means for receiving the impact of the door when the 25 latter is swung on its pivotal axis in engagement with said catch.

A still further object of the invention is generally to improve this class of devices so as to increase their utility, durability and 30 efficiency as well as to reduce the cost of manufacture.

Further objects and advantages will appear in the following description, it being understood that various changes in form, 35 proportions and minor details of construction may be resorted to within the scope of the appended claims.

In the accompanying drawings forming a part of this specification: Figure 1 is a side 40 elevation of a door stop constructed in accordance with my invention showing the pivoted locking member in engagement with a door. Fig. 2 is a top plan view of the door stop. Fig. 3 is a perspective view of the same. Fig. 4 is a plan view of the blank from which 45 the supporting frame is constructed.

Similar numerals of reference indicate corresponding parts in all of the figures of the drawings.

The improved door stop forming the subject matter of the present invention is principally designed for use in connection with

doors and similar closures and by way of illustration is shown in connection with a swinging door of the ordinary construction in which 5 designates the door and 6 the floor or other suitable support.

The device consists of a supporting frame 60 preferably stamped or otherwise formed from a single metallic blank of the construction shown in Fig. 4 of the drawings, said blank being provided with a reduced extension constituting a base 7 and oppositely disposed wings adapted to be folded laterally on the lines 8 to produce the side walls 9 of the supporting frame.

One end of each wing of the blank is folded inwardly on the line 10 to form vertically disposed strengthening lips 11, while the opposite end of each wing is bent on the folded lines 12 to produce flanges 13, there being longitudinal slits 14 formed in the metallic blank at the juncture of the extension and side wings thereof to permit the latter to be readily folded into the desired shape.

Suitable strips of rubber or other yieldable material 15 are seated in the flanges 13 to receive the impact of the door 5 when the latter is swung laterally in engagement with the door stop.

The side walls 9 are pierced by a plurality of transverse apertures 16 for the reception of a cotter pin 17 and upon which is mounted for pivotal movement between the walls 9 a spring locking member or catch 18.

The locking member or catch 18 is preferably stamped or otherwise formed of a single piece of spring metal one end of which is coiled around the pivot pin 17, while the opposite end thereof is bent upon itself and extended longitudinally in the direction of the pin 17 to form an over-hanging depressible catch or locking finger 19, the terminal of which is bent downwardly to produce a depending stop lip 20 adapted to bear against the adjacent face of the door and prevent accidental swinging movement of the latter.

The locking finger or catch 19 is inclined upwardly so as to guide the door to the locking recess formed between the lip 20 and the buffers 15.

Secured to the free end of the base 7 is a boss or enlargement 20' having a threaded opening formed therein for the reception of a

correspondingly threaded adjusting screw 21, the latter being provided with a kerfed head 22 adapted to bear against the lower face of the locking member at the pivoted end thereof thereby to adjust said locking member vertically of the frame so as to cause the locking member to engage doors spaced at different heights from the surface of the floor.

- 10 One or more coiled springs 23 are mounted on the cotter pin 17 each with one end thereof bearing against the locking member and with its opposite end engaging the adjacent reinforcing lip 11, thereby to normally and 15 yieldably support the free end of the locking member in engagement with the adjusting screw.

The device is secured in position on the floor by screws or similar fastening devices 20 24, a suitable notch or recess being preferably formed in the floor for the reception of the boss or enlargement 20.

It will thus be seen that when the door is 25 swung to open or partially open position the lower edge of the door will bear against the inclined face of the locking finger 19 and depress the same so as to permit the door to enter the recess between the lip 20 and buffer 15.

30 When it is desired to release the door the locking finger 19 is depressed thus permitting the door to be swung laterally to closed position in the ordinary manner.

By manipulating the screw 21 the free end 35 of the locking member or catch may be adjusted vertically so as to cause the lip 20 to bear against any desired portion of the door, while by changing the position of the cotter pin 17 the fixed or supported end of the locking member may be adjusted vertically of 40 the side walls of said supporting frame.

While the device is principally designed 45 for attachment to a floor it is obvious that the same may be secured to a wall or other suitable support and employed as a means for locking window blinds, swinging sashes and the like without departing from the spirit of the invention.

It will also be understood that the door 50 stops may be made of different sizes and shapes and the latter nickeled, japanned or otherwise coated to give the same a neat attractive appearance.

Having thus described the invention what 55 is claimed is:

1. A door stop including a supporting frame, a spring pressed locking member carried by the frame and adapted to engage the door for holding the latter in open or partially open position, and means for adjusting both ends of the locking member vertically of the frame.

2. A door stop including a supporting frame, a spring pressed locking member car-

ried by the frame for engagement with the door, means for adjusting both ends of the locking member vertically of the frame, and a buffer disposed in spaced relation to the active end of said locking member.

3. A door stop including a supporting frame, a locking member pivotally mounted on the frame for engagement with the door, and an adjusting screw carried by the frame and having its head arranged to bear against the lower face of the locking member at the free end thereof for adjusting said locking member vertically of said frame.

4. A door stop including a supporting frame having oppositely disposed side walls, a spring pressed locking member pivotally mounted between the side walls and adapted to engage the door, buffers secured to the side walls, and means carried by the frame and disposed beneath the free end of the locking member for effecting the vertical adjustment thereof.

5. A door stop including a supporting frame having oppositely disposed side walls, a locking member pivotally mounted between the side walls and provided with a spring pressed locking finger, buffers secured to the side walls and spaced from the adjacent end of the locking finger, and means carried by the frame and bearing against the free end of the locking member for effecting the vertical adjustment thereof.

6. A door stop including a supporting frame having oppositely disposed side walls provided with guide flanges, buffers seated between the flanges, a pin piercing the side walls, a spring actuating locking member mounted on the pin and provided with an overhanging locking finger for engagement with a door, and an adjusting screw carried by the frame and adapted to bear against the locking member for effecting the vertical adjustment of the latter.

7. A door stop including a supporting frame having oppositely disposed walls pierced by transversely aligned perforations, a pin extending through said perforations, a locking member secured to the pin and mounted for swinging movement between the side walls of the frame, said member being provided with an over-hanging locking finger, and means carried by one end of the frame and adapted to bear against the free end of the locking member for effecting the vertical adjustment of the same.

8. A door stop including a supporting frame stamped from a single metallic blank having a reduced extension and oppositely disposed side wings adapted to be folded upwardly to produce vertical walls, one end of each side wing of the blank being bent inwardly to form a lip and the other end thereof bent upon itself to produce a guide flange, a locking member pivotally mounted be-

tween the side wings of the supporting frame and provided with an over-hanging depressible finger for engagement with a door, buffers seated between the flanges, and means
5 carried by the supporting frame and bearing against the free end of the locking member for effecting the vertical adjustment thereof.

In testimony that I claim the foregoing as my own, I have hereto affixed my signature in the presence of two witnesses.

JNO. M. PATTERSON.
